HYDRAULIC VALVE TAPPET OPERABLE TO
VARY VALVE-LIFT AND VALVE-TIMING

Helmuth A. Meinecke, Grosse Pointe, Mich.

Application July 22, 1946, Serial No. 685,431

10 Claims. (Cl. 123—90)

1

This invention relates to valve mechanism for internal combustion engines and more particularly to hydraulic tappet mechanism for operating the exhaust and intake valves of such engines, an important object of the invention being to provide an improved hydraulic tappet of the self-adjusting or compensating type constructed and operable in improved manner to automatically vary the performance characteristics of the engine.

Heretofore, hydraulic tappets in commercial use have been employed in the operation of exhaust and intake valves for the purpose of eliminating tappet adjustment as well as providing automatic compensation or take-up for play or looseness between the tappet body and cam shaft consequent to clearance necessary for valve stem expansion, which in the case of conventional mechanical tappets frequently results in noisy operation of the valves. A conventional compensating tappet of the hydraulic type usually comprises a tubular tappet body having in the upper end thereof a plunger contacting the valve stem with the space in the tappet body below the plunger divided into two hydraulic chambers, the lower of which acting at all times as the reservoir for the other. A one way check valve is generally interposed between the chambers to prevent the oil or hydraulic medium from returning to the reservoir chamber, the construction being such that oil is trapped in the upper chamber during operation and provides an incompressible hydraulic column through which the thrust of the cam is positively transmitted to the valve without any appreciable lost motion, thus ensuring a constant and predetermined timing of the valve and a fixed opening and closing operation thereof.

One of the aims of the present invention is to provide a hydraulic tappet mechanism which will not only possess any or all of the advantages of the conventional self-adjusting or compensating tappet but additional important advantages in the improvement of the performance of the engine and in permitting efficient operation over a wider power and speed range. It is well known that an engine designed with high speed timing and large valve areas to give an early opening and late closing of the valve, as well as a relatively wide or large opening thereof, will produce up to at least one third more maximum power, but an engine so timed will either not run or will operate very inefficiently at low speeds. Conversely, an engine designed with low speed timing and small valve areas will operate advantageously at low speeds but will not give efficient performance

2

at high speeds. In view of these limitations it is customary to provide valve sizes and timing which are a compromise between the two extremes, yet whether such engines are equipped with ordinary mechanical tappets or conventional hydraulic compensating tappets the operation and performance characteristics are not satisfactory at the low and high speed limits of the particular engine, and furthermore the maximum power available in the engine is not utilized.

It is an object of the invention to overcome these disadvantages and to provide an engine having an improved hydraulic mechanism operable to vary the size of valve opening and the timing thereof in accordance with the engine speed so as to enable the engine to perform efficiently throughout the range from low to high speed while at the same time increasing the power output thereof.

20 A further object of the invention is to provide an engine in which the effective maximum opening of the valve, the timing thereof and the cam design are such as are suitable for high speed operation and maximum power output, these characteristics being obtained at high speed operation by transmitting the cam thrust to the valve without appreciable lost motion. However, the improved construction is such that as the speed is reduced a progressively increasing lost motion or telescoping action is introduced in the tappet mechanism between the cam and the valve altering the valve timing and reducing the lift or effective opening of the valve so as to maintain efficient operation. The compensating action is progressive between maximum high and low speeds and at the latter limit the lost motion or telescoping action of the tappet mechanism is greatest, thus affording the proper timing and valve opening needed to enable the engine to perform properly at the low speed limit.

45 A further object of the invention is to provide a self-adjusting or compensating hydraulic tappet mechanism wherein means is provided for maintaining and ensuring efficient and uniform operation irrespective of changes in viscosity of the oil or other lubricating medium occasioned by variations in the temperature thereof.

Still another object of the invention is to provide a hydraulic tappet device having a chamber interposed between telescoping parts of the tappet through which oil is circulated during operation, means being provided for controlling the oil circulation in accordance with the operating speed of the engine to vary the telescoping action of the tappet parts, the improved construction

and operation being such that the discharge of oil from the chamber incident to telescoping action of the tappet parts will be substantially constant regardless of variations in the viscosity of the oil due to temperature changes. This constant control of the oil discharge, constituting an important feature of the invention, may be accomplished on the one hand by the design and arrangement of the discharge orifice or orifices or on the other hand by varying the size of the discharge orifice through the relative expansion and contraction of metals having different coefficients of thermal expansion.

Other objects of this invention will appear in the following description and appended claims, reference being had to the accompanying drawings forming a part of this specification wherein like reference characters designate corresponding parts in the several views.

Fig. 1 is a vertical section of a portion of an internal combustion engine illustrating one embodiment of the present invention.

Fig. 2 is a central vertical section taken through the chambered tappet body shown in Fig. 1.

Fig. 3 is a fragmentary sectional view, similar to Fig. 2, but illustrating a modified form of discharge orifice.

Figs. 4, 5 and 6 are fragmentary sectional views similar to Fig. 3 but illustrating further modifications of the discharge orifice or orifices.

Fig. 7 is a side elevation of the tappet body shown in Fig. 6.

Fig. 8 is a fragmentary sectional view illustrating a modification in the construction of the tappet body housing.

Fig. 9 is a plan view, partly in section, of the tappet body shown in Fig. 8.

Fig. 10 is a fragmentary sectional elevation, similar to Fig. 1, but illustrating another embodiment of the invention.

Fig. 11 is a fragmentary sectional elevation illustrating still another embodiment of the invention.

Fig. 12 is an exploded view illustrating the piston, cap and discharge jet comprising three of the parts mounted within the chambered tappet body of Fig. 10.

Figs. 13 and 14 are detail sectional views illustrating slight modifications of the discharge end of the jet and the associated recess in the cap.

Fig. 15 is a sectional view taken substantially through lines 15—15 of Fig. 11 looking in the direction of the arrows.

Figs. 16 and 17 are views of the C-shaped spring shown in Fig. 15 which assists in supporting the inlet ball check valve.

Figs. 18 and 19 illustrate diagrammatically the time of opening and closing of the intake and exhaust ports during one cycle of engine operation in which low speed and high speed, shown respectively in these views, are obtained by virtue of this invention.

Fig. 20 illustrates a modified form of inlet check valve assembly.

Before explaining in detail the present invention it is to be understood that the invention is not limited in its application to the details of construction and arrangement of parts illustrated in the accompanying drawings, since the invention is capable of other embodiments and of being practiced or carried out in various ways. Also it is to be understood that the phraseology or terminology employed herein is for the purpose of description and not of limitation.

In the drawings several embodiments of the invention are illustrated as applied to an internal combustion engine of the multi-cylinder type comprising a cylinder block 20 bored at spaced intervals to receive a number of valve stem sleeves or bushings, one of such bushings 21 being herein illustrated. The exhaust and intake valves, one such valve 22 being herein illustrated, are of the poppet or mushroom type, each having a depending valve stem 23 slideable in one of the guide sleeves 21. Surrounding the lower portion of each valve stem is a compression spring 24 held in place at its lower end by a spring retainer 25, this spring normally urging the valve against its seat in accordance with conventional practice.

Referring to the embodiment of the invention illustrated in Fig. 1, the lower portion 20a of the cylinder block below the valve stems is formed with a number of vertically extending bores in line with the valve stems, each adapted to slidably receive a tubular or chambered tappet body 26 within the lower end of which is secured by a press fit an insert having a flat head 26a engageable by a cam lobe 27 secured to the cam shaft 28 of the engine.

Inasmuch as the various valves of the engine are controlled and operated in the same manner in accordance with the present invention, a description of the mechanism for accomplishing this purpose applicable to one valve will suffice.

The tappet body 26, shown in detail in Fig. 2, is formed with lower and upper cylindrical chambers 29 and 30 separated by a transverse partition wall 31 which is formed with a central hole 32. Extending within the upper chamber 30 of the tappet body is a hollow cylindrical check valve cage 33 having its lower reduced end 33a press fitted within the hole 32 in the partition wall 31. Threaded into the upper end of the check valve cage 33 is a disk 34 having a central hole 35. The lower reduced end 33a of the cage 33 is provided with a vertical hole 33b terminating at its upper end in a tapered seat engaged by a ball check valve 36. The cage 33 is provided adjacent the check valve with side ports 33a leading from the interior of the cage into the chamber 30.

Slidably fitted within the chamber 30 in the tappet body is a piston or plunger 37 terminating at its upper end in a reduced portion 37a engageable with the lower end of the valve stem 23, the piston 37 being removably held in position against withdrawal by means of a split ring 38 snapped into position within a circular groove in the upper end of the tappet body. Interposed between the piston 37 and the partition wall 31 and surrounding the check valve cage 33 is a relatively light compression spring 39 which is adapted to maintain the piston 37 in contact with the lower end of the valve stem 23.

The tappet body is provided immediately below the partition wall 31 with a number of holes or ports 40 which communicate with an annular groove 41 of somewhat greater height than the ports machined in the boss 20a of the cylinder block. The annular oil groove 41 communicates through a drilled passage 42 with a main oil inlet conduit 43 extending longitudinally in the cylinder block and connected to a source of lubricating oil such as the oil pump forming part of the lubrication system of the engine.

At a predetermined distance above the oil groove 41 there is machined in the boss 20a a second annular oil groove 44. Communication

between the upper chamber 30 of the tappet body and the oil groove 44 is obtained through the medium of a discharge port or orifice extending through the wall of the tappet body. In the embodiment shown in Figs. 1 and 2 the discharge orifice or port is in the form of a two-diameter hole comprising a relatively large hole 46 terminating in a relatively small hole 45 leading into the chamber 30. The two-diameter discharge orifice 45, 46 permits, as hereinafter more fully explained, a controlled discharge of oil from the chamber 30 into the oil groove 44 and thence into a sump or trough 47 extending longitudinally in the cylinder block. Excess oil over-flowing from this trough will spill into the crankcase of the engine.

In the embodiment of Figs. 8 and 9 the tappet housing 20a is modified to provide a relatively deep trough or reservoir 48 which communicates with both of the oil grooves 41 and 44. Oil from the engine lubrication system flows through a pipe 49 into the upper end of the trough 48, which is open to the atmosphere, maintaining the same filled at all times to overflowing. Oil flowing downwardly in the trough to the inlet oil groove 41 passes through a fine wire mesh screen 50 which acts as a baffle or filter to prevent the passage of air, foreign matter or gaseous oil bubbles into the space below the screen and, hence, into the inlet oil groove 41. The construction shown in Fig. 8 may be used with the tappet mechanism of the embodiment of Fig. 1 and has an advantage in that the tappets will operate quietly commencing with the first revolution of the engine crankshaft regardless of the oil pressure. A further advantage resides in the fact that air or gases picked up by the engine oil pump will escape from the upper part of the trough 48 before proceeding into the tappet body.

In Figs. 3 to 7 inclusive there are illustrated several modifications in respect to the discharge ports from the upper chamber 30 of the tappet body 26. In Fig. 3 the discharge port comprises a curved milled slot 51 in the outer wall of the tappet body which communicates centrally with a small drilled hole 52 leading into the chamber 30. In Fig. 4 the discharge port comprises a series of small holes 53 arranged in vertically spaced relation. These holes may be arranged in vertical alignment or may be staggered laterally while at the same time spaced vertically in the manner illustrated in Fig. 4. In Fig. 5 the exhaust port providing communication between the chamber 30 and the oil groove 44 comprises a small drilled hole extending through the wall of the tappet body, the top edge of this hole being located the desired distance from the top edge of the undercut oil groove 44 in the normal position of the tappet body. In Figs. 6 and 7 the discharge port comprises a relatively narrow vertical slot 55 which is believed to be the theoretically correct shape, this slot however having the disadvantage as compared with the previous embodiments of being more expensive and difficult to machine. The height of the slot 55 determines the duration or the length of time that the discharge of oil from the chamber 30 can occur at the beginning of every cycle of operation, the width of the slot determining how fast or at what rate the discharge can occur. The discharge characteristics of the narrow vertical slot 55 in the embodiment of Figs. 6 and 7 may be obtained by the two-diameter discharge ports of Figs. 2 and 3 or the vertically spaced holes 53 in Fig. 4 or by

the proper positioning of the small drilled hole 54 in Fig. 5. It is considered important, in order to cause the tappet to change timing with an increase or decrease of engine speed, that the discharge of oil from the upper chamber 30 of the tappet body through the discharge port be at a low rate but of considerable duration or length of time at the beginning of each cycle of operation. This important operating characteristic is achieved by forming the discharge ports in the tappet body in accordance with any one of the embodiments illustrated in Figs. 2 to 7 inclusive.

In the embodiment of the invention illustrated in Figs. 10 and 12 the tappet body comprises a relatively thin walled cylindrical member 56 differing from the tappet body of Fig. 1 by the elimination of the partition wall 31. The interior of the tappet body forms a chamber 57 closed at its lower end by means of a shoe or insert member 58 terminating in a flat head engaged by the cam lobe 21 on the cam shaft 28. Slidable within the upper end of the tappet body 56 is a piston 59 comprising an upper cylindrical head 59a (Fig. 12) having an undercut portion 59b intermediate its upper and lower ends forming with the wall of the tappet body an annular chamber or recess 60. The piston head 59a is formed with an integral depending hollow cylindrical stem 61 extending downwardly to a point proximate to the shoe or insert member 58, there being a predetermined clearance between the lower end of the stem 61 and the shoe 58 so as to permit the desired telescopic action of the piston and tappet body during operation. A number of radial ports or ducts 62 provide communication between an inner cylindrical chamber 63 in the piston 59 and the outer annular chamber 60. This latter chamber communicates with the undercut oil groove 44 in the tappet housing by means of a discharge port or duct 64.

Mounted within the piston 59 is a discharge jet stem 65 which terminates at its lower end in a head 65a fitting within the lower end of the stem 61 to provide a closure therefor, the head 65a being rigidly secured to the piston stem 61 as by means of a transverse pin. The portion of the jet stem 65 above the head 65a which extends through the piston stem 61 is of less diameter so as to provide a narrow annular chamber 66 around the jet stem. The piston stem 61 is provided with a number of vertically spaced ports 67 providing communication between the chamber 57 in the tappet body and the chamber 66 surrounding the jet stem 65. The latter is provided at a point immediately below the piston head 59a with aligned transverse holes 68 leading from the chamber 66 into a vertically extending passage 69 in the jet stem which is in the form of a hole drilled from the upper end of the jet stem downwardly to a point immediately below the transverse hole 68.

Secured by means of a press fit within a counterbore 63a in the upper end of the piston head 59a is a cap 70 which projects upwardly beyond the piston a sufficient distance to cause the upper end 70a of the cap to engage the lower end of the valve stem 23. The cap is bored to provide in its lower end a chamber 71 of larger diameter than the jet stem 65 and within which the upper end of this stem is housed, there being a clearance between the upper end of the jet stem and the upper wall 71b of the chamber 71. The cap 70 is maintained constantly in engagement with the lower end of the valve stem 23 by means of a

relatively light coil spring 72 surrounding the piston stem 61 and interposed between the shoe 58 and the bottom of the piston head. From the foregoing construction it will be seen that oil from the chamber 57 in the tappet body may flow through the ducts 67 into the chamber 66 surrounding the jet stem 65. Thence the oil may flow through holes 68 into the drilled passage 69 in the jet. Oil forced out of the upper end of the jet will pass into the chamber 63 in the piston head and thence outwardly through the holes or passages 62 into the annular chamber 60 formed by the undercut 59b in the piston head. From the chamber 60 oil may flow through the discharge port 64 in the tappet body into the outlet oil groove 44 and thence into the trough or sump 47.

Figs. 13 and 14 illustrate certain modifications in the construction of the cap 70 and upper end of the jet 65. In Fig. 13 the upper end of the jet is tapered to provide a substantially frustoconical end which is positioned within a conical recess 73 formed in the upper end of the chamber 71 in the cap. In Fig. 14 the upper end of the jet is counterbored to receive an insert 74 which may be of hardened steel to provide a nozzle which will be highly wear resistant against disintegration due to the velocity of oil forced out of the end of the nozzle or jet.

In the embodiment illustrated in Fig. 11 the construction is substantially the same as in the embodiment of Fig. 10 with the following exceptions. In this instance the upper drilled end 65a of the jet stem 65 is shortened so as to cause its upper discharge end to terminate at a point somewhat lower than the exhaust port 64 in the tappet body. Extending into a bore in the cap 70 and pinned thereto at 75 is a member 75 having a recess 75a in its lower end in line with the upper end of the jet, this member providing a cap for the jet suitably spaced from the upper end of the jet to permit the discharge of oil therefrom into the inner chamber 63 in the piston head. Oil from this chamber finds its outlet through the passages 62 into the outer chamber 60 in the piston head and oil from this chamber is discharged through the discharge port 64 into the undercut oil groove 44 and thence flows into a trough or sump 76. In this embodiment the trough 76 is similar to the trough 48 in Fig. 8, being in constant communication with the inlet and outlet grooves 41 and 44. A fine mesh wire screen 77 is mounted in the trough and functions similarly to the screen 50 in the embodiment of Fig. 8.

Referring to Figs. 15 to 17 inclusive, the tappet body in Figs. 10 and 11 is provided with an inlet passage 78 within which is rigidly secured a tubular insert member 79 terminating in a head 79a machined to provide a ball check seat. A C-shaped spring 80 is snapped into position within the tappet body 56 and has a hole 81 fitting over the head 79a so as to hold the spring in position. A leaf spring 82 is secured at one end to the end of the spring 80 and is formed at its opposite end with an apertured portion 83 receiving and retaining a ball check 84 cooperable with the tapered seat in the insert member 79.

In the embodiment illustrated in Fig. 20 the insert member 79 in the inlet passage 78 terminates in a ball check seat 85 adapted to be engaged by a resilient ball check 86 which may be formed of rubber-like material, such as neoprene or other synthetic or natural rubber substance. The ball check 86 is carried by a shroud or retainer member 87 which is secured to the end of

the leaf spring 82, the latter being supported by the C-spring 80 in the same manner as shown in Figs. 15 to 17 inclusive. The check valve constructions illustrated in the embodiments of Figs. 5 to 17 inclusive and 20 not only control effectively the flow of oil through the inlet passage 78 but also permit the mounting of the check valve within the tappet body without interference with the piston stem 61.

Heretofore, serious disadvantages and limitations have been encountered in conventional internal combustion engines on account of the fact that the effective opening and closing of valves have been fixed or constant. These characteristics have been governed by the size of valve and the contour of the cam selected for the particular engine. No appreciable variation in these characteristics occurs in the operation of the conventional engine throughout the speed range thereof. As a result an engine with a predetermined valve timing will only give satisfactory performance within a given speed range. For example, an engine having valve sizes and timing selected to permit efficient operation at relatively low speeds will be limited as to its upper speed range and will not produce the power obtainable from an engine timed for high speed operation. In Fig. 18 there is illustrated a typical low speed timing diagram in which the curve *x* represents the degrees of opening of the intake valve between the lines *x'* and *x''*, and the curve *y* represents the degrees of opening of the exhaust valve between lines *y'* and *y''*. The intake valve with this timing arrangement opens at a point 8° before top dead center and closes at a point 40° after bottom dead center. The exhaust valve opens 45° before bottom dead center and closes at a point 3° before top dead center. A relatively small overlap of the valve occurs with this timing permitting low speed operation. It will be understood that variations in the low speed timing shown in Fig. 18 will be made in order to suit the particular engine. In Fig. 19 there is illustrated, on the other hand, a typical timing diagram for a high speed engine having much higher maximum power output but incapable of operating efficiently at low speed. In this case the period of opening of the intake valve is from line *x'* to line *x''*, as shown by the curve *x*, the valve opening 43° before top dead center and closing 75° after bottom dead center. The period of opening of the exhaust valve, as shown by curve *y*, is from 80° before bottom dead center to a point 32° after top dead center. The much greater overlap of the exhaust and intake valves in this case permits the desired high speed operation and an engine timed in this manner will produce at least one-third more power than an engine timed according to the diagram of Fig. 18 but will not function efficiently at low speed.

Engines timed as in Figs. 18 and 19 are generally designed for special purposes. Hence, engines constructed for general purposes, such as for passenger automobiles, are given a compromise timing between these extremes. In accordance with a typical average speed timing the intake valve may open at 10° before top dead center and close at a point 40° after bottom dead center, and the exhaust valve may open at 50° before bottom dead center and close at 10° after top dead center.

It is possible by virtue of the present invention to obtain the advantages of low speed and high speed timing and intermediate timing in a single engine, hence enabling the engine to operate efficiently at maximum low and high speeds and

throughout the speed range therebetween. Accordingly, the exhaust and intake valve areas may be made large to give the maximum openings needed for maximum engine speed and the cams 27 designed so as to time the opening and closing of the valves are given the maximum lift to the valves at the top speed selected, such as the high speed performance available with the timing indicated in Fig. 19. However, by introducing into the tappet mechanism in accordance with the present invention a telescoping action which varies in direct proportion to the engine speed, and to control under all operating conditions the flow of oil induced by the telescoping action, it is possible to alter both the effective valve openings and the normally set timing shown, for example, in Fig. 19, and to progressively vary this timing as well as reduce the amount of effective opening of the valves so that a low speed timing, such as illustrated in Fig. 18, or any intermediate or average speed timing, will result at predetermined stages in the engine operation. In other words, by virtue of the telescoping action of the tappet mechanism, and the control of the oil flow, the timing and effective opening of the valves will be automatically altered to give the timing and valve opening needed for most efficient operation at all speeds.

The operation of the tappet mechanism shown in the embodiment of Fig. 1 is as follows. With the parts positioned as shown, oil under pressure from the inlet conduit 43 and inlet oil groove 41 will enter the chamber 29 in the tappet body through ports 40. From this chamber oil will flow through passage 33b past the ball check 36 into the ball check cage 33 and thence through ports 33a and 35 into the upper chamber 30 in the tappet body. Oil will flow out of the chamber 30 into the upper oil groove 44 through the exhaust port 45, or ports 52-55. Thus, with the parts positioned as shown in Fig. 1 a circulation of oil will be created from the inlet oil conduit 43 to the outlet sump or trough 47, the oil entering the tappet body through ports 40 and exhausting through port 45. As the tappet body 26 is lifted by the cam 27 the column of oil within the upper chamber 30 of the tappet body will decrease in height so long as the discharge orifice 45, 46 registers or is in communication with the oil groove 44 since oil during this time will be forced out of the chamber 30 into the outlet oil groove 44. While this occurs, the tappet body will telescope on the piston or plunger 37, moving upwards relatively to it without raising the valve. A lost motion between these parts is thereby created delaying the time of commencement of the opening of the valve 22, and this latter will not occur until the outlet or exhaust port 45, 46 is covered and an incompressible column of oil remains in the chamber 30 of the tappet body. As soon as this occurs the thrust of the cam will be transmitted from the tappet body 26 through the column of oil in chamber 30 to the piston 37, thereby raising the valve 22. The telescoping action of the tappet body and piston will compress the spring 39, and hence during closing movement of the valve the expansion of this spring will force the tappet body downwardly and ensure constant contact thereof with the cam.

It will be apparent that the amount of oil forced or pumped out of the tappet body chamber 30 through discharge port 45, 46 during the initial rise of the tappet body under the thrust of the cam will depend upon the size and location of

this port and the length of time that the port is in communication with the outlet oil groove 44, and hence the amount of oil thus discharged from the tappet body will determine the extent of telescopic action or lost motion travel of the tappet body relative to the piston 37. At the slowest speed of the engine, therefore, the telescopic action will be greatest, since the exhaust port or orifice 45, 46 remains uncovered for the longest interval of time. This results in a late opening of each valve, such as illustrated in Fig. 18. Moreover, since the telescopic action is greatest at this speed the cam will lift the valve the least height, thus providing the minimum effective opening past the valve.

As the engine speed is gradually increased, the exhaust port 45, 46 will remain uncovered for gradually shorter intervals of time, and hence the circulation of oil through the tappet body will progressively decrease. This will be accompanied by a progressive increase in height of the solid column of oil in the chamber 30 causing the cam to commence its lift of the valve at progressively earlier stages. As the height of this solid or incompressible column of oil in the tappet chamber increases, the height that the cam lifts the valve 22 will progressively and proportionately increase, and furthermore the timing of each valve will change giving an increasingly earlier opening and later closing thereof. At or near the top speed of the engine the exhaust port 45, 46 will reciprocate into and out of registry with the outlet oil passage 44 so rapidly that no appreciable amount of oil will be discharged. Under this operating condition there will be no appreciable telescopic action or lost motion between the tappet body and piston 37, and hence the valve operation will be substantially the same as if the tappet body and piston were one piece. This will make available the maximum power output with a high speed valve timing, such as is shown in Fig. 19 accompanied by maximum lift and effective opening of the valve.

It will be understood that during closing movement of the valve accompanied by expansion of the spring 39 oil will be drawn by suction from the lower chamber 29 in the tappet body past the check valve 36 into the upper chamber 30, thus replacing the oil that has been discharged from the upper chamber 30 during the telescopic action. By controlling the passage 33b by means of check valve 36 leakage of oil under high pressure from chamber 30 into chamber 29 and thence through the intake ports 40 and around the tappet body will be prevented.

An important feature of the invention resides in the size, shape and location of the exhaust port in the upper chamber 30. In order to obtain efficient results in respect to changes in timing consequent to changes in engine speed the discharge from the upper chamber, in the embodiment of Figs. 1 to 7 inclusive, should be at a low rate but over a considerable duration or interval of time during the beginning of the cycle of operation of the cam. Hence the height of the discharge port determines the duration or length of time that the discharge of oil from chamber 30 occurs and the width of the discharge port determines the rate of discharge.

Thus, in Figs. 1 and 2 the duration of discharge is determined by the relative heights of portion 46 of the discharge port and the outlet oil groove 44. Since the portion 45 of the exhaust port has a much smaller diameter or size than the portion 46 and a much less width or diameter than the

height of groove 44, a low rate of discharge will be produced. In the embodiment of Fig. 3 the milled slot 51 will give a discharge of oil of relatively long duration whereas the small hole 52, similar to hole 45, communicating therewith will give a low rate of discharge similar to that obtained in the embodiment of Figs. 1 and 2. In the embodiment of Fig. 4 the discharge port 53, consisting of a number of small vertically spaced holes similar to hole 45, will produce substantially the same results as in the embodiments of Figs. 2 and 3, giving a discharge of considerable duration of time but at a low rate. In the embodiment of Fig. 5 the small discharge port or orifice 54 is positioned so as to remain in communication with the oil groove 44 for the desired interval of time, and since the diameter of this port is considerably less than the height of the oil groove, as in the case of holes 45, 52 and 53, a relatively slow rate of discharge will occur. Similarly, in the embodiment of Figs. 6 and 7 the discharge port 55, which is in the form of a narrow slot similar in width to slot 51, will produce a low rate of discharge over a relatively long interval of time.

The operation of the device shown in Figs. 10 and 11 is substantially the same as above described. In these embodiments the amount of possible telescopic travel of the tappet body 56 relative to the piston 59 is determined by the clearance between the lower end of the piston stem 61 and the shoe 58. Upon engagement of the shoe with the lower end of the stem a positive mechanical lift of the valve will occur. In the embodiment of Fig. 1, on the other hand, the valve will be mechanically lifted upon engagement of the cage 33 with the lower end of the piston 31.

In Figs. 10 and 11 temperature controlled means is provided for controlling the flow of liquid through the exhaust port 64 and the outlet oil conduit in order to compensate for variations in viscosity of the liquid due to heating hereof. As a result of this construction it is possible to utilize an exhaust port 64 of uniform diameter and greatly increased effective size as compared with the previous embodiments, thus minimizing any danger of this port clogging during operation due to foreign matter in the oil supply.

Thermal control of the flow of oil through the port 64 is achieved in Fig. 10 by varying the clearance between the upper end of jet 65 and the juxtaposed face of the cap 70. For example, the piston 59 and cap 70 may be formed of steel and the jet 65 of a metal having a higher coefficient of thermal expansion, such as aluminum or magnesium. Assuming that it is desired to vary the discharge opening or clearance between the jet and cap from .003 of an inch to .006 of an inch in order to compensate for viscosity changes throughout the oil temperature ranges encountered in engine operation, then the relative lengths of the aluminum or magnesium jet and the steel piston will be selected so that the jet will expand a differential of .003 of an inch in a linear direction relative to the cap 70. Hence, with an initial clearance of .006 of an inch to accommodate oil having the maximum viscosity this clearance will gradually become smaller as the oil becomes hotter, and the reduction in this clearance will be in substantially direct proportion to the increase in oil temperature and the decrease in the viscosity thereof. Varying the clearance between the jet and cap in this man-

ner, therefore, amounts in effect to a variation in the size of the discharge port and enables the present device to operate efficiently and uniformly throughout the oil temperature range. It will be understood that the effective discharge opening of the jet may be varied to a greater or less extent than above described in order to suit the particular engine. Other metals, or alloys thereof, may also be utilized in order to obtain the desired differential in linear expansion and contraction rates between the jet and cap.

In the embodiment of Fig. 11 the jet member 65 is made shorter and the cap member 75 is formed of the same metal, such as aluminum, as the jet. These members are anchored at opposite ends to the piston. Hence, during operation the jet 65 and member 75 will expand toward each other relative to the piston 59 when heated in response to the rising temperature of the oil. Conversely, these parts will contract away from each other as the oil temperature drops. This will result in either reducing or increasing the effective discharge opening between the upper end of the jet and the juxtaposed surface 75a of the cap member. As in the embodiment of Fig. 10, the amount of this variation will be substantially directly proportionate to the variation in temperature of the oil and the variation in viscosity thereof.

I claim:

1. A cam actuated valve mechanism for actuating the valve of an engine, comprising a pair of relatively movable members having upper and lower communicating chambers adapted to have a hydraulic medium interposed therebetween in said chambers, a support within which one of said members is reciprocable, inlet and outlet conduits in said support, ports in said reciprocable member adapted to communicate with said conduits to provide for relative movement of said members at one time and adapted to reciprocate relative to said conduits during reciprocation of said reciprocable member to vary said relative movement, means for checking the flow of the hydraulic medium in one direction from one of said chambers, and means within one of said members responsive to the temperature of the hydraulic medium for controlling the flow of said medium through said outlet conduit to compensate for viscosity change of said medium.

2. A cam actuated valve mechanism for actuating the valve of an engine, comprising a pair of relatively movable members having upper and lower communicating chambers adapted to have a hydraulic medium interposed therebetween in said chambers, a support within which one of said members is reciprocable, inlet and outlet conduits in said support, ports in said reciprocable member providing communication between said conduits and chambers to provide for relative movement of said members at one time and adapted to reciprocate relative to said conduits during reciprocation of said reciprocable member to vary said relative movement, means for checking the flow of the hydraulic medium in one direction from one of said chambers, and means within one of said members responsive to the temperature of the hydraulic medium for controlling the flow of said medium through said outlet conduit to compensate for viscosity change of said medium.

3. In a hydraulic tappet mechanism for actuating the valve of an engine, a fixed body, a tappet including a pair of coaxial members arranged within said body in telescoping relation,

one of said members being chambered to contain a body of liquid interposed between the members and through which the thrust of a cam is transmitted to the other member for shifting the valve toward open position, inlet conduit means in the body and chambered member for introducing liquid into the latter, means for varying the rate of discharge of the liquid from the tappet thereby to vary the valve lift and timing thereof comprising outlet conduit means in the chambered member and body through which the discharge of liquid is governed by the speed of reciprocation and viscosity of the liquid, and means within said tappet responsive to the temperature of the liquid for controlling the flow of the liquid through said outlet conduit means to compensate for viscosity change of the liquid.

4. In a hydraulic tappet mechanism for actuating the valve of an engine, a fixed body, a tappet including a pair of coating members arranged within said body in telescoping relation, one of said members being chambered to contain a body of liquid interposed between the members and through which the thrust of a cam is transmitted to the other member for shifting the valve toward open position, inlet conduit means in the body and chambered member for introducing liquid into the latter, means for varying the rate of discharge of the liquid from the tappet thereby to vary the valve lift and timing thereof comprising outlet conduit means in the chambered member and body through which the discharge of liquid is governed by the speed of reciprocation and viscosity of the liquid, and means including an expansion element in said chambered member responsive to the temperature of the liquid for controlling the flow of the liquid through said outlet conduit means to compensate for viscosity change of the liquid.

5. In a hydraulic tappet mechanism for actuating the valve of an engine, a fixed body, a tappet including a pair of coating members arranged within said body in telescoping relation, one of said members being chambered to contain a body of liquid interposed between the members and through which the thrust of a cam is transmitted to the other member for shifting the valve toward open position, inlet conduit means in the body and chambered member for introducing liquid into the latter, means for varying the rate of discharge of the liquid from the tappet thereby to vary the valve lift and timing thereof comprising outlet conduit means including a port in the wall of the chambered member adapted to intermittently communicate with a passage in said body to provide for relative telescoping movement of the members and shiftable out of communication with said passage to provide a substantially positive hydraulic connection between the members, and means within said tappet responsive to the temperature of the liquid for controlling the discharge of the liquid through said outlet conduit means to compensate for viscosity change of the liquid.

6. In a hydraulic tappet mechanism for actuating the valve of an engine, a fixed body, a tappet including a pair of coating members arranged within said body in telescoping relation, one of said members being chambered to contain a body of liquid interposed between the members and through which the thrust of a cam is transmitted to the other member for shifting the valve toward open position, inlet conduit means in the body and chambered member for introducing liquid into the latter, means for varying the rate of discharge of the liquid from

the tappet thereby to vary the valve lift and timing thereof comprising outlet conduit means including a port in the wall of the chambered member adapted to intermittently communicate with a passage in said body to provide for relative telescoping movement of the members and shiftable out of communication with said passage to provide a substantially positive hydraulic connection between the members, and means including an expansion element in the chambered member responsive to the temperature of the liquid for controlling the discharge of the liquid through said outlet conduit means to compensate for viscosity change of the liquid.

7. In a hydraulic tappet mechanism for actuating the valve of an engine having a fixed body, a tappet including a pair of coating members arranged in said body for relative movement, one of said members being chambered to contain a body of liquid through which the thrust of a cam is transmitted to the other member for lifting the valve, inlet means for introducing liquid into said chambered member, means for varying the rate of discharge of the liquid from the tappet thereby to vary the valve lift and timing thereof comprising outlet conduit means in the tappet and body through which the discharge of liquid is governed by the speed of reciprocation and viscosity of the liquid, and means in said tappet responsive to the temperature of the liquid for controlling the discharge of liquid through said outlet conduit means to compensate for viscosity change of the liquid.

8. A hydraulic tappet mechanism comprising a support having a cylindrical bore, a reciprocable tappet body in said bore having a liquid chamber, a plunger associated with said body and adapted to receive the thrust of said tappet body through the column of liquid in said chamber, means for introducing liquid into said chamber, means for varying the discharge of liquid from the chamber thereby to vary the valve lift and timing thereof comprising a conduit in said support opening into said bore and adapted to register with a port in said tappet body constructed to discharge liquid therefrom in amounts varying in substantially direct proportion to the viscosity of the liquid, and temperature responsive means in said tappet body for controlling the discharge of liquid to compensate for viscosity change of the liquid.

9. In a hydraulic tappet mechanism for actuating the valve of an engine having a fixed body, a tappet including a pair of coating members arranged in said body for relative movement, one of said members being chambered to contain a body of liquid through which the thrust of a cam is transmitted to the other member for lifting the valve, inlet means for introducing liquid into said chambered member, means for varying the rate of discharge of the liquid from the tappet thereby to vary the valve lift and timing thereof comprising outlet conduit means in the tappet and body through which the discharge of liquid is governed by the speed of reciprocation and viscosity of the liquid, and means within said tappet responsive to the temperature of the liquid for controlling the flow of said liquid through one of said conduit means to compensate for viscosity change of the liquid.

10. In a hydraulic tappet mechanism for actuating the valve of an engine having a fixed body, a tappet including a pair of coating members arranged in said body for relative movement, one of said members being chambered to contain

a body of liquid through which the thrust of a cam is transmitted to the other member for lifting the valve, inlet means for introducing liquid into said chambered member, means for varying the rate of discharge of the liquid from the tappet thereby to vary the valve lift and timing thereof comprising outlet conduit means in the tappet and body through which the discharge of liquid is governed by the speed of reciprocation and viscosity of the liquid, means within said tappet responsive to the temperature of the liquid for controlling the flow of said liquid through one of said conduit means to compensate for viscosity change of the liquid, and check valve means for checking the flow of liquid in one direction in said chambered member.

HELMUTH A. MEINECKE.
